UNITED STATES PATENT OFFICE.

JOSEPH A. KRANTZ, OF DOVER, OHIO, ASSIGNOR TO THE REEVES MANUFACTURING COMPANY, OF DOVER, OHIO, A CORPORATION OF OHIO.

MACHINE FOR FORMING EAVES TROUGHS.

Application filed April 17, 1922. Serial No. 554,088.

To all whom it may concern:

Be it known that I, JOSEPH A. KRANTZ, a citizen of the United States, residing at Dover, in the county of Tuscarawas and 5 State of Ohio, have invented a new and useful Machine for Forming Eaves Troughs, of which the following is a specification.

This invention relates to dies for forming eaves-trough and has for its objects to provide dies by means of which an eaves-trough is completely formed from a sheet or strip of metal in a single pressing operation of the dies.

The above and other objects may be attained by providing dies such as illustrated in the accompanying drawings, in which—

Figure 1 is a side elevation of portions of the dies showing the same in the initial position;

20 Fig. 2, a section on the line 2—2, Fig. 1;

Fig. 3, a similar section showing the initial movement of the dies;

Fig. 4, a section on the line 4—4, Fig. 1, showing the final movement of the dies; and

25 Fig. 5, an end elevation of the finished eaves-trough.

Similar numerals refer to similar parts throughout the drawings.

The device comprising the present invention 30 contemplates a plurality of dies arranged to press the eaves-trough by a single operation of the dies and includes the lower fixed die 1 arranged to be mounted in fixed position upon the bed of any suitable form 35 of press.

The lower die 1 has a longitudinal half-round channel 2 formed in its upper face of substantially the same contour as the body portion of the eaves-trough. A plurality of 40 spring pressed plungers 3 normally protrude upward through the bottom of the channel 2 for the purpose of kicking the finished eaves-trough out of the lower die after each complete operation of the dies.

45 The upper movable dies comprise the central forming die 4 carried upon the reciprocating head 5, the bending die 6 carried upon the reciprocating head 7 and the bead forming die 8 carried upon the reciprocating head 9.

The heads 5, 7 and 9 may be vertically reciprocated by any usual and well known means, the head 5 being operated independently of the heads 7 and 9 which may 55 operate in unison.

The forming die 4 is provided with the half-round portion 10 arranged to fit within the channel 2 leaving a sheet like space between the dies. A quarter round cut-out 11 is provided in the side of the die 4 adjacent to the bending die 6 and conforming to the rounded inner surface 12 of the bending die. 60

The bending die 6 is provided with the T-shaped guide ribs 13 slidably mounted for horizontal movement in the guide blocks 14 which are suspended by means of the sliding pins 15 mounted for vertical movement through the head 7. 65

One or more angular cams 16 are fixed to the upper surface of the bending die 6 and arranged to co-act with similar cams 17 fixed to the under surface of the head 7. It will thus be seen that as the head 7 is depressed and the lower surface of the bending die 6 is brought into engagement with the upper surface of the lower die 1, a continued downward movement of the head 7 will cause the bending die to be moved inwardly to the position shown in Fig. 4. 75

The bead forming die 8 is fixed to the lower portion of the head 9 as by bolts 18 and is provided on its under side, adjacent to the die 4, with the bead forming channel 19 arranged to be moved into engagement with the lower die 1, as shown in Fig. 4 to 80 form a bead upon one side of the eaves-trough. 85

In the operation of the device, a blank sheet or strip of metal as indicated at A, is placed upon the lower die 1 in the position shown in Fig. 2. The head 5 is then depressed, forcing the central portion of the sheet A into the channel 2 as shown in Fig. 3, the heads 7 and 9 remaining in the raised position. 90

The heads 7 and 9 may then be lowered in unison, or each of said heads may be lowered independently after the head 5 has been lowered. As the bead forming die is lowered, the upwardly extending edge portion of the sheet, indicated at B in Fig. 3, will be received into the bead forming channel 19 of the die 8, rolling said edge portion of the sheet into a bead, as shown at C in Fig. 4. 95

As the head 7 is lowered, the under side of the bending die 6 will first engage the upper surface of the lower die 1, after which a continued downward movement of the head 7 will, through the cams 16 and 17, slide the bending die 6 inwardly, the round- 100

105

110

ed bending surface 12 thereof engaging the upturned edge portion D of the sheet and bending the same around the surface 11 of the die 4, as indicated at E in Fig. 4.

5 In raising the dies to the initial position, the head 7 may first be raised, the inner edge of the bending die 6 riding against the cam surface 20 of the die 4, sliding the bending die outward to its normal position with reference to the guide blocks 14. The head 9 may, if desired, be raised at the same time, although this is immaterial. When the head 5 is raised, the spring pressed plungers 3, will automatically kick the finished eaves-trough, as shown in Fig. 5, out of the channel 2 of the lower die.

10 The finished eaves-trough will comprise the body portion A' of substantially half-round cross sectional contour, provided with 20 the bead C upon one edge. The portion E of the eaves-trough is bent inwardly by the bending die in order to allow for a certain spring in the metal, this side of the finished 25 eaves-trough springing out as indicated at 25 E' in Fig. 5, producing a substantially half-round trough.

15 If desired, a suitable spring may be provided to assist in moving the bending die 6 outward to its normal position with relation 30 to the guide blocks 14, although as above described, this movement may be accomplished through the cam 20.

20 It will be evident from the above description and the illustration of the device in the 35 accompanying drawings, that a simple and efficient means is provided for pressing an eaves-trough from a blank sheet in a single 40 operation of the device, overcoming the difficulties heretofore encountered in the manufacture of eaves-trough, simplifying the 45 manufacture of eaves-trough and lessening the cost of the same.

50 It should be understood that the device may be operated equally well to form eaves-trough having a bead upon each edge, a second bead forming die being substituted for the bending die, the operation of the device being otherwise the same as above described.

I claim:—

55 1. A device for forming eaves-trough from a sheet comprising a fixed die having a channel therein, a forming die arranged

to be depressed to press the central portion of a sheet into said channel, said forming die having a rounded cut-out in one side, a 55 bending die arranged to be depressed after the depression of the forming die, means for moving the bending die inward to press the adjacent edge portion of the sheet into the cut-out, and a bead-forming die arranged to 60 be depressed after the forming die and having a channel arranged to receive the adjacent edge portion of the sheet to roll a bead thereon.

2. A device for forming eaves-trough 65 from a sheet comprising a fixed die having a channel therein, a forming die arranged to be depressed to press the central portion of a sheet into said channel, said forming die having a rounded cut-out in one side, a 70 head arranged to be depressed after the depression of the forming die, a bending die upon said head, coacting cam surfaces upon the head and bending die for moving the bending die inward to press the adjacent 75 edge portion of the sheet into the cut-out of the forming die, and a bead-forming die arranged to be depressed after the forming die and having a channel arranged to receive the adjacent edge portion of the sheet to roll a 80 bead thereon.

3. A device for forming eaves-trough 85 from a sheet comprising a fixed die having a channel therein, a forming die arranged to be depressed to press the central portion of a sheet into said channel, said forming die having a rounded cut-out in one side and a cam surface communicating with the cut-out, a head arranged to be depressed after the depression of the forming die, co- 90 acting cams upon the head and bending die for moving the bending die inward to press the adjacent edge portion of the sheet into the cut-out as the head is depressed, the cam surface in the forming die being arranged to coact with the bending die to move the bending die outward as the head is raised, and a bead-forming die arranged to be depressed after the forming die and having a 95 channel arranged to receive the adjacent edge portion of the sheet to roll a bead 100 thereon.

JOSEPH A. KRANTZ.
